UNITED STATES PATENT OFFICE.

ALBERT STEFFIN, OF NEW BEDFORD, MASSACHUSETTS.

DESIGN FOR A GLASS VESSEL.

No. 39,643.

Specification for Design.

Patented Oct. 27, 1908.

Application filed November 29, 1907. Serial No. 404,469. Term of patent 7 years.

To all whom it may concern:

Be it known that I, ALBERT STEFFIN, a citizen of the United States, residing at New Bedford, in the county of Bristol and State of Massachusetts, have invented a new, original, and ornamental Design for a Glass Vessel, of which the following is a specification, reference being had to the accompanying drawing, forming part thereof.

The figure is an elevation showing my new design.

The design resides in the ornamentation of the vessel as shown in the drawing consisting of one main stem A extending from the base of the vessel and terminating in a tulip flower a at the top with leaves b, b, branching

from each side of such stem near the base; a higher third leaf c being of larger size and extending in a curve to near the top of the vessel. A shorter stem B extends from the base with two leaves d, d, and terminates at the top in a tulip flower f. A leaf stem C extends from the base between the two stems A and B.

What I claim as my invention is—

The ornamental design for a glass vessel as shown and described.

ALBERT STEFFIN.
